ELECTRICAL CONDUCTOR OF THE SUSPENDED CABLE TYPE

Donald H. Scofield, Redwood City, Calif., assignor to
Insul-8-Corp., San Carlos, Calif., a corporation of California

Application March 26, 1959, Serial No. 55,206

Term of patent 14 years

(Cl. D26—1)

Fig. 1 is a perspective view of an electrical conductor of the suspended cable type, showing my new design; Fig. 2 is a bottom plan view, the top being substantially a mirror image thereof; and

Fig. 3 is a side elevational view, the opposite side being substantially a mirror image thereof.

The broken line showing of wires in Fig. 1 is for illustrative purposes only.

I claim:

The ornamental design for an electrical conductor of the suspended cable type, as shown and described.
